(57) **CLAIM**

We claim the ornamental design for a guitar pick holder, as shown and described.

DESCRIPTION

FIG. 1 is a front elevational view of a guitar pick holder showing our new design:

FIG. 2 is a rear elevational view thereof;

FIG. 3 is a bottom plan view thereof;

FIG. 4 is a top plan view thereof;

FIG. 5 is a right side elevational view thereof;

FIG. 6 is a left side elevational view thereof; and,

FIG. 7 is a front perspective view thereof.

The guitar picks depicted by broken lines in FIG. 7 have been shown for the purpose of illustrating environment that forms no part of the claimed design.

The dashed lines in FIGS. 1, 2, and 7 are understood to represent stitching.

The textured pattern shown in FIGS. 1, 2, and 7 is continuous throughout the surfaces to which it is applied.
